UNITED STATES PATENT OFFICE.

FRANS T. STRÖBECK, OF BEACHMONT, MASSACHUSETTS, ASSIGNOR TO THE SINGER MANUFACTURING COMPANY, A CORPORATION OF NEW JERSEY.

WORK-GUIDE FOR SEWING-MACHINES.

1,342,775.

Specification of Letters Patent.

Patented June 8, 1920.

Application filed June 6, 1918. Serial No. 238,553.

To all whom it may concern:

Be it known that I, FRANS T. STRÖBECK, a subject of the King of Sweden, residing at Beachmont, in the county of Suffolk and

5 State of Massachusetts, have invented certain new and useful Improvements in Work-Guides for Sewing-Machines, of which the following is a specification, reference being had therein to the accompanying drawings.

10 This invention relates to work-guides for sewing machines and has for a primary object to provide a device for controlling a strip of fur-material, either natural or artificial, as it is presented to the needle of a 15 sewing machine, so that the fur or pile-fibers will be deflected or bent over to one side during their approach to the needle, whereby the stitches will be laid across the bent over base-portions of the pile-fibers along an edge 20 of the fur-strip.

A further object of the invention is to provide a fur-guiding attachment which may be placed in advance of the presser-foot of an ordinary sewing machine to bend or deflect 25 the fur to one side so that the pile-fibers along an edge of the fur-strip will be bent over transversely of the line of seam-formation and delivered to the presser-foot in such bent over condition.

30 With the above and other objects in view, as will hereinafter appear, the invention has been embodied in a machine having a reciprocating needle and a rotary looper operating to enchain the needle-loops with one 35 another to form readily raveling stitches. The machine is preferable equipped with a presser-foot feeding mechanism including a four-motion feed-dog, and a flat work-support; the latter carrying an edge-guide including an overhanging lip for controlling 40 the edge of the fur-strip farthest away from the stitching line.

Operating in conjunction with the foregoing devices is a fur-guide for deflecting 45 the fur or pile-fibers to one side or toward the edge-guide above referred to. The fur-guide may comprise a sheet-metal strip disposed in advance of the presser-foot and curved widthwise to catch the pile-fibers at 50 the edge of the fur-strip adjacent the stitching line and gradually bend them over transversely of the line of feed as they are drawn toward the presser-foot, whereby when they reach the upwardly and forwardly curved 55 toes of the presser-foot, they will pass under

the latter in a transversely bent condition. The lower edge of the fur-guide is held spaced slightly above the work-supporting plate to allow the marginal portion of the backing strip which supports the pile-fibers 60 to pass under it. This edge of the fur-guide extends in the direction of feed but is disposed at the side of the line of seam-formation opposite that at which the edge-guide lies and acts upon the base-portions of the 65 pile-fibers to keep the opposite edge of the fur-strip in contact with the edge-guide.

When the bent over pile-fibers reach the stitching point, they will lie across the line of seam-formation and will be basted down 70 to the backing strip in bent over condition. The presser-foot is formed in its under face with a vertical guiding wall forming substantially a continuation of the lower edge of the curved fur-guiding plate. 75

The fur-basting operation above indicated is particularly useful in carrying out a novel process of attaching fur-material to the tops of house-slippers, which process forms the subject matter of my copending application 80 Serial No. 238,554, filed herewith, and is hereinafter briefly described. The present invention, however, is of general utility in stitching along the edge of fur-material or pile-fabric wherein it may be desirable to 85 baste down the pile-fibers so that they will lie transversely of both the needle-path and the line of seam-formation preliminary to further stitching operations upon the basted 90 fur-strip.

In the accompanying drawings, Figure 1 is a front elevation of a sewing machine embodying the invention. Fig. 2 is a plan view of the cloth-plate of the machine. Fig. 3 is a cross-section along the line 3—3, Fig. 2, 95 with a strip of fur-material in position. Fig. 4 is a perspective view of the presser-foot. Fig. 5 is a cross-section of the presser-foot and throat-plate on the line 5—5, Fig. 2 with the work in position. Fig. 6 is a 100 side elevation of the parts shown in Fig. 2. Figs. 7 to 11, inclusive, illustrate a method of attaching fur-material to the top edge of a felt slipper, the carrying into effect of which method the present invention is designed to 105 facilitate.

In the preferred embodiment of the invention, as illustrated, the machine frame comprises the base 1 supporting the raised bed 2 from which rises the standard 3 carry- 110

ing the overhanging bracket-arm 4 terminating in the hollow head 5. Mounted on the bed 2 is the flat cloth-plate 6 which is apertured as usual for passage of the reciprocating needle 7 and the four-motion feed-dog 8; the latter operating in conjunction with a spring-pressed presser-foot 9 the upwardly curved forward extremity of which is bifurcated to form toes 10 and 11. The longitudinal half of the presser-foot sole-portion including the toe 10 is thickened as by means of a plate 12 secured to the under surface of the presser-foot, to form a work-engaging surface 13 disposed below the level of the work-engaging surface 14 of the other longitudinal half of the presser-foot which includes the toe 11. The work-engaging surfaces 13 and 14 of the presser-foot are therefore stepped in arrangement and at their juncture a vertical guide-wall 15 is formed extending lengthwise of the presser-foot.

As the present mechanism is intended for a basting operation, the machine is provided with a looper 7^x of the rotary type which co-operates with the needle 7 in the usual manner to form readily raveling stitches.

Adjustably secured to the cloth-plate 6 by thumb-screws 16 is the edge-guide 17 having an edge-guiding wall 18 parallel to the line of seam-formation and an overhanging lip 19 designed to keep the edge of the work from riding or curving above or over the wall 18. In basting fur strips, such as shown at *a*, Fig. 3, preparatory to attaching them to the tops of slippers, the guide 17 is adjusted so that the distance between the free edge of the lip 19 and the guide-wall 15 of the presser-foot is approximately equal to the width of the pile-forming portion 2 of the fur-strip; it being noticed that the pile-supporting base *b* of the fur-strip is somewhat wider than the fur portion *a*.

To bend the fur away from the needle 7 or toward the edge-guide 17 so that the fur may be bent transversely of the line of seam-formation and may pass under the toes 11 of the presser-foot, a fur-deflecting guide 20 is employed. The guide 20 may consist of a strip of sheet-material curved widthwise and supported by an arched bracket 21 screwed to the guide 17. The strip 20 has a lower edge 22 which is straight along the major portion of its length and is spaced slightly above the cloth-plate 6 to afford clearance for the passage of the base *b* of the fur strip, Fig. 3. Throughout the major portion of its length the lower edge 22 of the fur-guide 20 extends substantially in the direction of feed but is disposed a short distance to one side of the vertical plane defined by the needle-path and the line of seam-formation, in order that the line of stitches may be formed within the pile-supporting portion of the backing strip *b* and bind down the base-portion

of the pile-fibers along the edge of the fur-strip. The rearwardly disposed end of the fur-guide 20 is curved over somewhat more sharply than the forward end and terminates closely and preferably beneath the upwardly curved extremity of the presser-foot toe 11.

In the operation of the device, a strip of fur such as shown in cross-section, Figs. 3 and 7, is introduced into the channel defined by the guides 20 and 17. As the fur-strip passes toward the stitching point the guide 20 acts to bend over the pile-fibers, as indicated in Fig. 3, and present them in bent over condition to the presser-foot which holds them in flattened condition, Fig. 5, while the needle forms a row of chain stitches *c* serving to bind down the pile-fibers in bent over condition. The fur-strip is then reversed and the opposite edge basted in a similar manner; the basted fur-strip having the pile-fibers *a* crowded toward the center as shown in Fig. 8.

One edge of the backing strip *b* of the fur-material is next attached by a line of fastening stitches *d* to the edge of a body-fabric *e* which may constitute the top of a felt slipper. This operation may be performed on an ordinary sewing machine since the bent back pile-fibers are held out of the way of the reciprocating needle of the machine and do not interfere with the assembling of the edge of the backing strip *b* upon the edge of the body-fabric *e* with the pile-fibers *a* between the plies *b* and *e* and in contact with the outer or "right" side of the body-fabric *e*, Fig. 9.

After the stitches *d* have been formed, the backing strip *b* of the fur-material is folded about the stitches *d* and the edge of the body-fabric *e* into the position shown in Fig. 10, in which position a line of fastening stitches *f* passing through the backing strip *b* and body-fabric *e* may be readily formed by an ordinary sewing machine; the pile-fibers being still held by the basting stitches out of the way of the sewing needle. Upon thereafter raveling or pulling out the basting stitches *c*, the fur expands into the roll-like form shown in cross-section, Fig. 11, and provides the desired finish at the top edge of the body-fabric or the upper edge of the slipper, effectively concealing the backing strip and all stitching.

Having thus set forth the nature of the invention, what I claim herein is—

1. In a sewing machine for basting pile-fabric, the combination with sewing mechanism for forming a line of through-and-through stitches, and a presser-foot, of a fur-bending guide located mainly in advance of the presser-foot and operating to bend over the pile-fibers along an edge of the fabric and guide them into contact relation with the under surface of the presser-

foot, said fur-bending guide being so positioned laterally with relation to the stitching line that the stitches formed will bind down the bent over base-portions of the pile-fibers while leaving the remaining portions of the pile-fibers unconfined.

2. In a sewing machine, in combination, a frame including a work-support, stitch-forming mechanism including a reciprocating needle and complemental loop-taking mechanism supported at opposite sides of said work-support, four-motion feeding mechanism including a feed-dog operating through an aperture in the work-support, a 10 presser-foot opposed to said feed-dog, edge-guiding means disposed at one side of the line of seam-formation for guiding a strip of fur-material to the needle, and a fur bending guide disposed alongside and acting in opposition to said edge-guide to bend the fur transversely of the direction of feed and guide it under said presser-foot.

3. In a sewing machine, in combination, a frame including a work-support, stitch-forming mechanism including a reciprocating needle and complemental loop-taking mechanism supported at opposite sides of said work-support, four-motion feeding mechanism including a feed-dog operating 25 through an aperture in the work-support, a presser-foot opposed to said feed-dog, edge-guiding means disposed at one side of the line of seam-formation for guiding a strip of fur-material to the needle, and a fur-guide in advance of the presser-foot and spaced from said work-support for bending the fur transversely of the direction of feed and guiding it under the presser-foot.

4. In a sewing machine, the combination 40 with a reciprocating needle and a presser-foot, of an edge-guide located at one side of the line of seam-formation, and a fur-guide having a surface-portion at the opposite side of the line of seam-formation for guiding 45 the base-portions of the pile-fibers at one edge of the fur-strip, said fur-guide having additional surface-portions for bending the

fur toward said edge-guide and delivering it to the presser-foot in bent over condition, whereby the stitches will be formed across 50 the bent over base-portions of the pile-fibers along the edge of the fur-strip.

5. In a sewing machine, in combination, a reciprocating needle, feeding mechanism, a presser-foot having a stepped work-engaging surface including a vertical guiding wall extending in the direction of feed, an edge-guide opposed to said guiding wall and forming therewith a guiding channel for reception of a strip of fur-material, and 55 a fur-guide for bending the pile-fibers laterally of the line of seam-formation and delivering them to the presser-foot in bent over condition across the line of seam-formation.

6. Work-guiding mechanism for sewing machines comprising, a work-supporting plate, an edge-guide mounted on said work-supporting plate, and an elongated fur-guiding plate disposed in advance of the 70 presser-foot and having its lower edge spaced slightly above said work supporting plate, said fur-guiding plate being curved widthwise to bend the pile-fibers of a strip of fur-material laterally of and across the 75 line of seam-formation.

7. Work-guiding means for sewing machines comprising, a work-supporting plate, an edge-guide mounted on said work-supporting plate, and a fur bending guide having 80 a concaved surface opposed to said edge-guide, as and for the purpose specified.

8. In a sewing machine, the combination with stitch-forming mechanism including a reciprocating needle and a presser-foot, of 85 an edge-guide having a guiding portion disposed in advance of said needle, and a fur bending guide disposed mainly in advance of said presser-foot and having a curved side-wall extending alongside of and co-operating with said edge-guide.

In testimony whereof, I have signed my name to this specification.

FRANS T. STRÖBECK.
